DESIGN FOR A PIANO CASE

Wilbur M. Day, Norwood, Ohio, assignor to The Baldwin Company, Cincinnati, Ohio

Application January 12, 1938, Serial No. 74,255

Term of patent 7 years

To all whom it may concern:

Be it known that I, Wilbur M. Day, a citizen of the United States, residing at Norwood, in the county of Hamilton and State of Ohio, have invented a new, original, and ornamental Design for a Piano Case, of which the following is a specification, reference being had to the accompanying drawing, forming part hereof.

The drawing is a perspective view of the piano case showing my new design.

The distinctive feature of the design resides in the concavity of the main case of the piano below the keyboard, as shown.

I claim:

The ornamental design for a piano case, as shown and described.

WILBUR M. DAY.
